UNITED STATES PATENT OFFICE.

GEORGE J. OBERMEYER, JR., OF WEST BEND, WISCONSIN.

MAIL-BOX POST.

Application filed August 9, 1926. Serial No. 128,012.

This invention relates to an adjustable platform.

Objects of this invention are to provide an adjustable platform of novel construction, which may be securely anchored in the ground, and which will support a mail box, with parcel post matter, milk bottles, or other articles, as desired.

Further objects are to provide a novel form of metal platform supported by a tubular post-like member of telescopic construction, and provided with channel iron supports to secure the utmost strength with a minimum amount of material. Further objects are to provide a novel form of adjustable platform, which is so constructed that it may be securely attached to the ground adjacent a roadway, and in which provision is made for supporting the platform and post not only by the flat surface of the ground, but also by the slanting surface adjacent the usual ditch on the side of the roadway.

An embodiment of the invention is shown in the accompanying drawings in which:

Figure 1 is a side elevation partly in section of the apparatus;

Figure 2 is a sectional view on the line 2-2 of Figure 1;

Figure 3 is a sectional view on the line 3-3 of Figure 1;

Figure 4 is a sectional view on the line 4-4 of Figure 1.

Referring to the drawings, it will be seen that the device is composed of a supporting post 1, which is of tubular construction. This post or pipe carries a lower pointed end 2, which may be driven into the ground. It is provided with a plurality of apertures 3 adjacent its lower portion within which pins 4 carried by the upturned portions 5 of the horizontal supporting feet 6 are adapted to pass. These supporting feet are channel shape throughout their body portion, and are rounded at the upturned portions 5, as shown most clearly in Figures 1 and 3. Each of the members 6 or supporting feet have pins, as shown in Figure 1, and its corresponding pin 4 is slipped into the aperture 3. Thereafter, the ring 7, which is in the form of a clamp, is positioned about the upturned lips 5, and is clamped by means of the bolt 8, thus securely locking the parts together.

It is to be noted that the bolt 8 forms a

pivot pin for the slanting arm 9. This slanting arm may be adjusted at any angle desired, and as shown in Figure 2, it readily cooperates with the slanting face of a ditch. The pivotally mounted arm is provided with a slidible extension 10, which is telescopic upon the portion 9. It is guided at its rear end by means of the clip 11. At the outer end of the member 9, a clamp 12 is provided, as shown most clearly in Figure 4. This clamp binds the members 10 and 9 rigidly together in the desired adjusted position. Further, this clamp is provided with outwardly extending arms drawn together by means of the bolt 13. This bolt furnishes a pivot pin for the brace 14, which extends angularly upwardly to the central post 1. At the upper end, it is provided with a clamp 15, which may be securely locked to the post 1, and is provided with a clamp 15, which may be securely locked to the post 1, after the desired adjustment has been secured.

It is to be noted from Figure 1, that each of the feet 6 is provided with a channel iron brace 16 riveted thereto, and extending upwardly and inwardly to the central post 1. These braces have upturned lips 17 which are provided with pins 18 adapted to enter corresponding apertures formed in the post 1. A clamp 19 surrounds the lips 17 and holds them rigidly in engagement with the posts.

The upper end of the tubular member 1 receives the cap-like fitting 20, which is provided with an aperture through which the slidible rod or tubular member 21 projects. The member 21 may be either solid or tubular.

A set screw 22 passes through the fitting 20, and may serve to lock the stem 21 against rotation. However, a collar 23 is adjustably carried by the shank 21, and is locked thereto by means of the set screw 24. Thus, if it is desired, the set screw 22 may be loosened and the rod or shank 21 may be rotated.

This member 21 is provided with a fitting at its upper end equipped with an outwardly extending flange 25, which is riveted, brazed, spot welded, or otherwise secured to the plate 26. A plurality of diagonally outwardly and upwardly extending braces 27 are secured to the rod 21, and extend outwardly to the corners of the rectangular plate 26. The angle irons continue upward-

ly, as indicated at 28, at the ends of the plate, and are provided with apertures through which longitudinal and transverse bolts or rods extend. These rods are indicated in Figure 1 by the reference characters 29 and 30 respectively. They form guide rails for the platform and prevent articles placed thereon from falling from the platform.

10 It is to be understood that although this device is eminently suited for holding mail boxes, that nevertheless, other articles may be carried by the platform, as desired.

In using the device, the pointed central support 1 is driven into the ground at the desired point. Thereafter, staples 31 are driven into the ground and over the arms 6, the desired angular adjustment of the telescopic arms 9 and 10 is secured, and the 20 clamps 12 and 15 are locked. Thereafter, a staple 34 is driven into the ground and straddles the projecting portion 10 of the arm.

It will be seen, therefore, that the device 25 is of eminently practical and easily produced construction.

It will be seen further that the device may be most readily positioned and that the maximum firmness of attachment to the 30 ground is secured by this construction.

Not only does the device secure support from the main member 1, but also it is supported very rigidly by means of the outwardly extending arms 6, and the angular 35 adjustable arms.

It will be seen, therefore, that a very simple and serviceable type of device has

been provided, which may be used for any number of different purposes.

It is to be distinctly understood that the 40 terms "rod" and "tubular member" are used synonymously in this description.

Although the invention has been described in considerable detail, such description is intended as illustrative rather than limiting 45 as the invention may be variously embodied and as the scope of such invention is to be determined as claimed.

I claim:

1. A supporting platform, comprising a 50 central standard adapted to be driven into the ground, a plate of rectangular contour carried by the upper end of said standard, a plurality of braces secured at one end to said standard and secured adjacent the other 55 end to the corners of said plate, said braces having upwardly extending corner portions, and a plurality of longitudinally and laterally extending rods joining said corner portions.

2. A supporting platform, comprising a central standard, a supporting member carried by the upper end of said standard, a plurality of horizontally extending feet adapted to be rigidly secured to said standard, and a third foot adjustably locked to said standard and adapted to extend at an angle to the plane of the other feet.

In testimony that I claim the foregoing I have hereunto set my hand at West Bend, 65 in the county of Washington and State of Wisconsin.

GEORGE J. OBERMEYER, Jr.
